(57) **CLAIM**

The ornamental design for container with cover, as shown and described.

DESCRIPTION

FIG. 1 is an expanded perspective view of a container with cover showing my new design;

FIG. 2 is an expanded perspective view of a second embodiment of FIG. 1;

FIG. 3 is an expanded perspective view of a third embodiment of FIG. 1;

FIG. 4 is a top plan view of FIG. 1;

FIG. 5 is a bottom plan view of FIG. 1;

FIG. 6 is a front elevational view of FIG. 1;

FIG. 7 is a right side elevational view of FIG. 1;

FIG. 8 is a left side elevational view of FIG. 1; and,

FIG. 9 is a rear elevational view of FIG. 1 thereof.

FIGS. 4-9 are drawn in an enlarged scale with the container cover placed on the container.
